(57) **CLAIM**

The ornamental design for an picture frame, as shown and described.

DESCRIPTION

FIG. 1 is a front perspective view of an picture frame, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is another front perspective view thereof, shown in an alternate position of use.

The broken lines in the drawings illustrate the portions of the picture frame, which form no part of the claimed design.
